SUBMARINE

Jakob Hojnowski, Nekoosa, Wis.

Application December 7, 1937, Serial No. 178,576

4 Claims. (Cl. 114—16)

This invention relates to certain new and useful improvements in submarines.

An object of this invention is to provide a submarine equipped with propellers with a part of the mechanism for the support of the propellers being adjustable for changing the direction of propelling force of the propeller blades to aid the submarine in quicker downward and upward travel under water.

10 A further object of the invention is to provide a submarine with laterally positioned adjustable fins for directing underwater movement of the submarine.

15 A still further object of the invention is to provide a submarine with captive floats secured to the submarine by means of a cable wound upon a drum and releasable from the submarine to float upon the water and also to provide a submarine with life rafts that may be entirely disengaged from the submarine.

20 With the above and other objects in view that will become apparent as the nature of the invention is better understood, the same consists in the novel form, combination and arrangement of parts hereinafter more fully described, shown in the accompanying drawings and claimed.

In the drawings:

25 Figure 1 is a top plan view, partly broken away and shown in section of a submarine constructed in accordance with the present invention and illustrating forwardly positioned adjustable propellers, laterally positioned fins and a gun carried by a hatch cover that is opened to operative position;

30 Figure 2 is a side elevational view of the submarine shown in Figure 1, the lateral fins being illustrated by dotted lines in shifted positions;

35 Figure 3 is a fragmentary vertical longitudinal sectional view of the submarine shown in Figures 1 and 2;

40 Figure 4 is a detail sectional view taken on line 4—4 of Figure 1, showing the devices for adjusting the direction of propelling force of the propeller blades;

45 Figure 5 is a detail sectional view taken on line 5—5 of Figure 1, showing a part of the drive mechanism for the propellers;

50 Figure 6 is a detail sectional view taken on line 6—6 of Figure 1, showing the adjustable housing carrying the drive shaft and the propeller shaft driven thereby;

55 Figure 7 is a top plan view of another form of submarine having propellers positioned at the front and rear ends thereof;

55 Figure 8 is a fragmentary horizontal sectional

view of the front end of the submarine shown in Figure 7, illustrating the dual motors;

5 Figures 9 and 10 are detail sectional views taken on line 9—9 and 10—10 respectively of Figure 8, showing the manually operated devices for changing the direction of propelling force of the propeller blades;

10 Figure 11 is a top plan view of another form of submarine embodying forwardly positioned propellers, laterally positioned hinged fins and compartments for captive and releasable floats;

15 Figure 12 is a detail sectional view taken on line 12—12 of Figure 11;

15 Figure 13 is a detail sectional view taken on line 13—13 of Figure 11;

Figure 14 is a detail sectional view taken on line 14—14 of Figure 11; and

20 Figure 15 is a detail sectional view taken on line 15—15 of Figure 11.

Referring more in detail to the accompanying drawings, and particularly to Figures 1 to 6, there is illustrated a submarine comprising a hull or body 20 having a tapering substantially pointed bow or front end 21, a rear propeller 22 and a rudder 23. The top deck 24 of the submarine 25 body 20 carries a cabin hood 25 located adjacent the front end thereof.

25 A disappearing gun 26 is associated with the upper deck 24 of the submarine and is carried by the underside of the cover 27 that is hinged 30 as at 28 to the edge wall of the hatch opening 29. The cover 27 when in closed position with respect to the hatch opening 29 seals said opening and positions the gun 26 interiorly of the body 20 of the submarine, as shown by dotted lines in 35 Figures 2 and 3. A receptacle 30 is suspended within the submarine body 20 from the upper deck 24 thereof and is closed at its upper side by means of a pair of covers 31 hinged at their outer edges as at 32 to opposite sides of the upper edge of the 40 receptacle 30 with the meeting edges of the cover sections 31 rabbed for interfitting engagement and retained in closed position as shown in Figure 1 by means of pivoted latches 33 operated by handles 34 that are adapted to be engaged with 45 keepers 35 as shown in Figure 1 for retaining the latches 33 engaged with one of the cover sections 31. A life raft 36 is normally confined within the receptacle 30 and rises by its buoyance to the surface of the water when released from the receptacle.

50 An automatically operated stabilizing vane 37 is associated with each side of the submarine body 20 intermediate the ends thereof with said vanes located substantially midway the top and 55

bottom of the submarine, said vanes 37 being fixed to a pair of shafts 38 journalled in bearings 39 located interiorly of the submarine body, the inner ends of the shafts 38, each carrying a bevelled pinion 40 engaged with a bevel gear 41 that is automatically operated by a gyroscopic device 42 that is diagrammatically illustrated, the stabilizing vanes 37 operating to maintain the submarine body on an even keel.

10 Sets of manually controlled vanes are arranged on the opposite sides of the submarine body, respectively forwardly and rearwardly of the stabilizing vanes 37 for controlling the underwater direction of travel of the submarine and as shown in Figures 1 to 3, a shaft 43 is journalled in bearings transversely of the submarine body 20 adjacent the forward end thereof with each laterally extending end of the shaft 43 carrying a vane 44 fixed to the shaft intermediate its ends. A 20 pair of vertically aligned horizontal shafts 45 and 46 is journalled transversely of the submarine body 20 rearwardly of the stabilizing vanes 37, the shafts 45 and 46 being connected together for simultaneous operation by link and arm devices 25 47 while a pair of arms 48 respectively carried by the shafts 43 and 45 are connected by a longitudinally extending link 49 for the simultaneous operation of the forward vane 44 and the double rear vanes 50 secured to the projecting ends of 30 the rear shafts 45 and 46.

The operating means for the shafts 43, 45 and 46 is shown more clearly in Figs. 1 to 3 and includes a worm shaft 51 journalled in bearings 52 with the operating handle or wheel 53 therefor located in the cabin hood 25 in proximity of the operator's seat 54. The worm shaft 51 has a worm portion 55 engaged with a worm segment 56 fixed to the shaft 43 intermediate the ends thereof as illustrated. When the worm shaft 51 is operated, rotary motion is imparted to the shaft 43 and 45 and through the medium of the arm and link devices 47 to the shaft 46 for simultaneous operation of the vanes 44 and 50 for controlling the underwater direction of travel 45 of the submarine.

The propeller blade 22 at the rear end of the submarine constitutes the main propulsion means therefor and a pair of propeller blades 57 respectively located at opposite sides of the front tapering end 21 of the submarine body and in propulsion of the submarine and are adjustable for cooperation with the side vanes 4 and 50 to add a direct propelling force to the direction of underwater travel of the submarine. As illustrated in Figs. 1 to 6, a shaft 58 extending transversely of the forward tapered end 21 of the submarine body is journalled in a pair of tubular bearings 59 which are in turn journalled in bearings 60 carried by the submarine body 20 and as shown more clearly in Figs. 1 and 5, a bevel gear 61 is secured to the shaft 58 intermediate its ends and has the pinion 62 meshing therewith, said pinion 62 being carried by the shaft 63 of the motor 64. The adjacent inner ends of the rotatable tubular bearings 59 have the side leg portions 65 of a U-shaped strap 66 anchored thereto as at 67 for normally holding said strap and tubular bearings 59 against rotative movement while manually controlled devices are associated with said strap 66 for rotatably shifting the tubular bearings 59 and the propeller blades 57 carried by the outer ends of the tubular bearings.

As shown more clearly in Figures 1 and 6, a housing 68 is anchored to the outer end of each 75 tubular bearing 59 and into which housings the

outer ends of the shaft 58 respectively extend and carry a bevel gear 69. A propeller shaft 70 is journalled in the housing 68 transversely of the end of the shaft 58 and carries a bevel gear 71 meshing with the bevel gear 69, the propeller blade 57 being secured to the end of the shaft 70 projecting forwardly of the housing 68.

For holding the two housings 59 against rotative movement during operation of the shaft 58 for the operation of the propeller blades 57 and also 10 for rotatably adjusting the tubular bearings 59 for changing the direction of propelling force of the propeller blades 57, devices are provided which are shown more clearly in Figs. 1, 3 and 4 and include a worm shaft 72 journalled in bearings 73 15 within the submarine body 20 and having an operating handle or wheel 74 at its upper end. The lower end of the worm shaft 72 carries a worm 75 that is engaged with a worm segment 76 secured to one of the side legs 65 of the U-shaped strap 20 66 at the point 77 with the shaft 58 journalled to said worm segment 76 as illustrated. It will be understood that when the worm shaft 72 is rotated, corresponding movement is imparted to the U-shaped strap 66 through the worm 75 and worm 25 segment 76 and from said strap 66 to the tubular bearings 59 carrying the housings 60 at the outer ends thereof and in which housings the propeller shafts 70 are journalled.

In the form of invention illustrated in Figs. 7 to 10, the submarine body 20a carries a pair of forwardly positioned propellers 57a, similar to the propellers shown in Figs. 1 to 6 and a pair of laterally disposed rearwardly located propellers 22a, the top deck of the submarine body 20a having a cabin hood 25a and carrying a receptacle for a life float with the receptacle covered by the hinged covers 27a while another receptacle carried by the top deck forwardly of the cabin hood 25a houses a captive float with the receptacle 40 closed by hinged covers 18. In this form of the invention, the propellers 57a are carried by shafts journalled in housings 68a at the outer ends of tubular bearings 59a and the shaft 58a journalled through said housings 59a carries a pair of bevelled gears 61a that are respectively engaged by pinions 62a driven by the separate motors 64a. The shaft 58a may be driven by either or both of the motors 64a under control of the clutch devices 79 associated with the motor shaft carrying the pinions 62a. A pair of U-shaped straps 66a has the shaft 58a journalled through the side legs thereof, the straps being adjacently positioned with the outer leg of each strap anchored respectively to the inner end of the adjacent tubular bearing 59a while the worm segment 76a is secured as at 77a to the adjacent legs of said U-shaped straps and between said legs. The worm 75a carried by the worm shaft 72a imparts rotative movement to the housings 59a for changing the direction of pulling force of the propellers 57a.

As shown in Figs. 11 to 15, the submarine body 20b carries a pair of stabilizing vanes 37b at opposite sides thereof between the front and rear ends of the submarine, while transversely aligned pairs of vanes 44b and 50b are respectively carried forwardly and rearwardly of the stabilizing vanes 37 at opposite sides of the submarine and said vanes 44b and 50b are hingedly mounted at 70 their forward ends as at 80. A pair of forwardly positioned propellers 57b is carried by the submarine and are adjustable in a manner as described in connection with the other forms of the invention. A life raft 36b is carried in the re- 75

ceptacle 30b suspended from the top deck 24b of the submarine body and the rabbetted meeting edges 81 of the cover sections 27b are retained in closed position by latch devices 33b carried by 5 operating handles 34b which in turn are engaged with keepers 35b. A captive float 82 is normally confined within a receptacle 83 suspended from the top deck 24b of the submarine body, the cover sections 18b of the receptacle 83 being retained 10 in closed position by means of latch devices 84 operated by handles 85 located interiorly of the submarine body. The captive float 82 is attached to one end of a cable 86 that is wound upon the drum 87 in the receptacle 83 so that when the 15 latch devices 84 are released, the cover sections 18b of the receptacle 83 automatically open and the float 82 rises to the surface of the water.

From the above detailed description of the invention, it is believed that the construction and 20 operation thereof will at once be apparent and while there are herein shown and described the preferred embodiments of the invention, it is nevertheless to be understood that minor changes 25 may be made therein without departing from the spirit and scope of the invention as claimed.

I claim:

1. In a submarine of the character described, 30 a body portion, propellers adjustably carried by the forward end of the body portion and means associated with the propellers and operable from within the body portion for changing the direction of pulling force of the propellers to aid the submarine in its underwater travel upwardly and downwardly, said means including a shaft extending transversely of the body portion, rotatable bearings for the shaft with the propellers carried by the bearings, a motor drive for the shaft and means for rotatably adjusting the bearings, including a strap having side walls rigidly connecting the bearings, a worm segment 35 fixed to a side wall of the strap and through which the shaft rotatably extends and a manually operated worm shaft engaged with the segment for operation thereof.

2. In a submarine of the character described, 40 a body portion, propellers adjustably carried by the forward end of the body portion and means associated with the propellers and operable from within the body portion for changing the direction of pulling force of the propellers to aid the submarine in its underwater travel upwardly and downwardly, said means including a shaft extending transversely of the body portion, rotatable bearings for the shaft with the propellers carried by the bearings, a motor drive for the 45 shaft and means for rotatably adjusting the bearings, lateral fins movably carried by the body portion and means for positioning the fins to control the direction of underwater travel of the submarine, there being at least three sets of fins

with the fins of each set transversely alined at each side of the submarine, a gyroscopic device associated with the intermediate set constituting stabilizers, the front set being manually adjustable and means connecting the front and rear 5 sets for simultaneous operation for controlling the direction of underwater travel of the submarine.

3. In a submarine of the character described, a body portion, propellers adjustably carried by the forward end of the body portion and means associated with the propeller and operable from within the body portion for changing the direction of pulling force of the propellers to aid the submarine in its underwater travel upwardly and 10 downwardly, said means including a shaft extending transversely of the body portion, rotatable bearings for the shaft with the propellers carried by the bearings, a motor drive for the shaft and means for rotatably adjusting the 15 bearings, including a worm segment fixed to the bearings and a worm shaft engaged with the segment for operation thereof, lateral fins movably carried by the body portion and means for positioning the fins to control the direction of 20 underwater travel of the submarine, there being at least three sets of fins with the fins of each set transversely alined at each side of the submarine, a gyroscopic device associated with the intermediate set constituting stabilizers the front 25 set being manually adjustable and means connecting the front and rear sets for simultaneous operation for controlling the direction of underwater travel of the submarine.

4. In a submarine of the character described, 30 a body portion, propellers adjustably carried by the forward end of the body portion and means associated with the propellers and operable from within the body portion for changing the direction of pulling force of the propellers to aid the submarine in its underwater travel upwardly and 35 downwardly, said means including a shaft extending transversely of the body portion, rotatable bearings for the shaft with the propellers carried by the bearings, a motor drive for the shaft and means for rotatably adjusting the 40 bearings, including a strap rigidly connecting the bearings, a worm segment fixed to the strap and a worm shaft engaged with the segment for operation thereof, lateral fins movably carried by the body portion and means for positioning the 45 fins to control the direction of underwater travel of the submarine, there being at least three sets of fins with the fins of each set transversely alined at each side of the submarine, the intermediate set constituting stabilizers and the front 50 and rear sets being manually adjustable for controlling the direction of underwater travel of the submarine.

JAKOB HOJNOWSKI. 60
